ENDLESS TRAVELING WATER SCREEN

Lloyd G. Bleyer, Milwaukee, Wis., assignor to
Chain Belt Company, Milwaukee, Wis., a corporation of Wisconsin

Original application March 15, 1930, Serial No.
436,212. Divided and this application September 23, 1931, Serial No. 564,661

4 Claims. (Cl. 210—175)

This invention relates to endless traveling water screens and has for one of its objects to improve the construction of prior devices of this character whereby they may be rendered more efficient in use and less expensive in maintenance.

The invention relates more particularly to endless traveling water screens of the type which comprises a pair of laterally spaced endless chains, which pass around vertically spaced sprockets, each link of which chains has secured to it a screen basket through which the water passes in order that the refuse carried thereby may be separated out upon the screen surface. It has been found in the actual operation of such screens, especially where the water contains relatively large amounts of harsh abrasive substances, such as foundry slag, coal cinders and the like that excessive wear occurs upon the pintle rolls of the chains, necessitating frequent removal and renewal of these rolls. Inasmuch as these pintle rolls are usually mounted intermediate the spaced side bars of the chain links and since the screen baskets are secured to said side bars, it has heretofore been necessary to disconnect the chain bars from the baskets and to dismantle the chain in order to remove worn pintle rolls.

Traveling water screens of this character are usually provided, in addition to the head and tail sprockets around which the chains pass, with intermediate vertical guide members with which the pintle rolls engage during the vertical up-run of the screen and it is the travel of the rolls along these vertical guides which results in the greatest wear on the said rolls, since they do not ordinarily contact with the boot sprocket wheels. Therefore, if provision is made to eliminate the engagement of the pintle rolls with the vertical intermediate guide members during the up-run of the screen, while at the same time providing suitable support for the screen baskets and chains throughout this up-run—since the water pressure is usually sufficient to make such support necessary or desirable—the major portion 45 of the wear which now occurs upon the pintle rolls may be eliminated.

It is, therefore, the primary object of the present invention to provide means which, while furnishing the necessary lateral support for the chains and baskets on the up-run of the screen, will relieve the chain pintle rolls from their engagement with the vertical guides and thereby eliminate, to a great extent, the wear which now occurs thereon.

55 A further object of the invention is to provide

means for accomplishing the above desirable result comprising additional rollers or members which may engage the vertical guides to furnish the necessary horizontal support, which rollers or members are so mounted as to be readily accessible to the end that they may be removed and replaced without the necessity of dismantling the chain and disconnecting the screen baskets.

With the above and other objects in view which will appear as the description proceeds, the invention consists in the novel details of construction and combinations of parts more fully hereinafter described and particularly pointed out in the appended claims.

Referring to the accompanying drawings forming a part of this specification in which like reference characters designate like parts in all the views:

Figure 1 is a side elevational view, partly broken away, of a well known form of endless traveling water screen embodying the present invention;

Figure 2 is an enlarged vertical sectional view through the articulating joint of a pair of screen baskets;

Figure 3 is an elevational view of the parts shown in Figure 2 as seen from the right of the said figure; and

Figure 4 is a horizontal sectional view taken approximately on the plane indicated by the line 4—4 of Figure 2 looking in the direction of the arrows.

Referring more particularly to the said drawings there is illustrated an endless traveling water screen, comprising a frame-work 15 upon which are journaled head sprockets 16, about which pass the endless chains 17 constituting the supports for the screen baskets 18. The frame 15 comprises in part the vertically extending Z-bars 19, one flange 20 of which is receivable in grooved socket members which are imbedded in the side walls 22 of the water conduit. The webs 23 of the Z-bars 19 extend parallel to the faces of the walls 22 and the forward flanges 24 of the said bars 19 extend inwardly to form trash seals with the fabricated side members 25 of the screen baskets, as is well known in the art. Boot or tail sprockets 26 are suitably journaled upon the framework 15 adjacent the bottom of the water conduit and the chains 17 pass around these sprockets, as will be readily understood.

Intermediate the sprockets 16 and 26 there is provided the vertically extending angles or guides 27 which constitute in conjunction with the rolls to be hereinafter described the means for taking

the horizontal thrust imposed upon the screen by the force of the water as it flows therethrough. The chains 17 are provided with pintle rolls 28 which are journaled upon bushings 34 surrounding the chain pins 29, and in previous constructions these pintle rolls have engaged with the vertical guides 27 during the up-run of the chain to furnish the necessary horizontal support for the screens. These pintle rolls engage the teeth 30 of head sprockets 16 whereby motion may be imparted to the chains and screens, but ordinarily the boot sprockets 26 are so formed or cut away as at 31 that the said rolls do not contact therewith.

15 As above stated the pintle rolls 28 of the chains 17 are ordinarily mounted intermediate the side bars 32 of the said chains and when wear occurs upon such rolls obviously the chain pins 29 must be withdrawn and the chains and baskets disconnected in order that such rolls may be removed and renewed. This is a rather difficult and expensive procedure and in order to eliminate the necessity therefor, I have provided the additional rolls 33 journaled upon readily removable stub shafts 36 mounted in extensions 37 of the fabricated side members 25 of the screen baskets. As will be clearly seen from Figure 1 these rolls engage the vertical guides 27 during the up-run of the screen and serve to transmit the horizontal thrust of the said baskets to the vertical guides 27, while at the same time maintaining the pintle rolls 28 out of engagement with the said vertical guides whereby the objectionable wear upon the same may be eliminated.

30 35 As will be clear from Figures 3 and 4 the additional rolls 33 are off-set inwardly, or in other words are out of alignment with the pintle rolls 28, and therefore the said additional rolls do not engage with either the head or the boot sprockets. If necessary the peripheral flanges of these sprockets may be slightly cut away in order to clear the said rolls 33, as will be readily understood by those skilled in the art.

40 45 If, after long continued use, the additional rolls 33 or their pintles show excessive wear they may of course be readily removed and replaced without disturbing the chain pintles 29 or the chain pintle rolls 28 and dismantling the chain, for the said additional rolls 33 are entirely independent of the chain connections and may be

readily removed and replaced without reference to the latter.

This application is a division of my prior co-pending application entitled Endless traveling water screens filed March 15, 1930, Serial No. 436,212, now Patent No. 1,874,736 dated August 30, 1932. 80

It is obvious that those skilled in the art may vary the details of construction as well as the precise arrangement of parts without departing from the spirit of the invention, and therefore it is not wished to be limited to the above disclosure except as may be required by the claims. 85

What is claimed is:

1. In an endless traveling water screen, a basket supporting chain; screen baskets secured to said chain; a guiding sprocket for said chain; an additional guiding element adjacent said sprocket; and thrust rolls carried by said baskets, engageable with said additional guiding element. 90

2. In an endless traveling water screen, a plurality of basket supporting chains having sprocket-engaging pintle rolls; screen baskets secured to said chains; guiding sprockets for said chains; additional guiding elements offset laterally inwardly with respect to said sprockets; and thrust rolls mounted on said baskets in alinement and engageable with said offset guiding elements. 95

3. In an endless traveling water screen, a basket supporting chain having sprocket-engaging pintle rolls; screen baskets having side members having extensions secured to said chain; a guiding sprocket for said chain; an additional guiding element offset laterally with respect to said sprocket; and thrust rolls mounted in the extensions of the side members of said baskets in alinement and engageable with said offset guiding member. 100

4. In conveying apparatus, a pair of spaced traveling chains; load-carrying elements secured to said chains to travel therewith; fixed supporting elements offset laterally and transversely of said chains; and thrust elements carried by said load-carrying elements intermediate said pair of chains and engageable with said supporting elements, said thrust elements by reason of their position being readily mountable and demountable without dismantling said chains. 115
